UNITED STATES PATENT OFFICE.

WILLIAM YOULTEN, OF HOVE, ENGLAND, ASSIGNOR TO HARRY SEYMOUR FOSTER, OF WESTMINSTER, ENGLAND, AND LOUIS NAPOLEON SCHOENFELD, OF HOVE, ENGLAND.

MACHINE FOR OPENING AND CLEANING FIBROUS MATERIAL.

Application filed November 14, 1921. Serial No. 515,101.

To all whom it may concern:

Be it known that I, WILLIAM YOULTEN, a subject of the King of Great Britain and Ireland, residing at 25 Brunswick Square, 5 Hove, in the county of Sussex, England, have invented certain new and useful Improvements in Machines for Opening and Cleaning Fibrous Material, of which the following is a specification.

10 This invention relates to machines for opening and cleaning fibrous material, and refers to apparatus of the class in question, by means of which much of the said material, can be cleaned and prepared for use in 15 industry in a more economical and satisfactory manner than has hitherto been the case.

The machine constructed according to my present invention, comprises a rectangular or like frame provided with an inner preferably elliptical chamber in which are mounted a series of beaters arranged spirally on a drum or its equivalent presenting a serrated surface. The said beaters are adapted to revolve at a high rate of speed.

25 Means are furnished for introducing the material to be treated, so that it shall be brought under the influence of the beaters and freed from dust and other solid matter which is dealt with by special means constituting an important feature of the invention.

Means are also added for the expulsion of the treated material.

Devices are further provided by means of 35 which the quantity, moment of introduction and exit of the material is automatically controlled.

In this connection the invention includes 40 automatic controlling mechanism for operating the base and product valves, said mechanism being constructed to permit the turning of the opening and closing of said valves and the duration of the treatment of the material in the apparatus to be easily 45 and quickly adjusted whilst the apparatus is in operation without it being necessary to stop the machine whilst such adjustments are being made. This feature is of considerable importance as it permits the machine 50 to be readily adjusted to obtain the most effective results from material varying within wide limits in quality.

The construction of the discharge valve or flap and the mechanism for operating the

same are constructed to ensure the correct 55 opening and closing thereof, suitable means being provided for permitting the extent of opening of said valve to be limited so as to change the direction in which the discharge of the material takes place.

60 Apparatus for the conveyance and removal from the machine of the material under treatment is also preferably combined with the said machine as hereinafter more fully described.

65 In order that the invention may be readily understood, I will now proceed to describe the preferred construction according to the invention reference being made to the accompanying drawings, in which:—

70 Fig. 1 is a side view of the machine.

Fig. 2 is a front view.

75 Fig. 3 is a side elevation to a larger scale and partly in section showing the automatic controlling mechanism for the base and product valve.

Fig. 4 is a side elevation partly in section of Fig. 3.

80 Fig. 5 is a sectional view of Figure 3, the section being taken approximately on the line 5—5 of that figure.

Figs. 6 and 7 are side elevation and front view respectively of a modified arrangement of links or levers forming part of the mechanism for operating the base feed valve or 85 flap.

Fig. 8 is a side elevation and,

Fig. 9 a front elevation, also to a larger scale, showing the elliptical chamber in which the beaters rotate, each of said views 90 being shown partly in section.

Fig. 10 is an end view of the beater shown in Fig. 9 and indicated by dotted lines in Fig. 8.

95 Figs. 11, 12 and 13 are side view front view and plan respectively of one of the spirally arranged arms or studs on the beater.

Fig. 14 is a view showing a simple method of securing the arms or studs to the beater 100 shaft.

Fig. 15 is a perspective view showing the preferred construction and arrangement of the discharge flap.

105 The frame of the machine comprises two side members 10 of cast or wrought iron embracing between them a rectangular sheet iron enclosure 11 provided with a pair of

doors 12, 12 on one side hinged at 13 to the side members 10 and secured when closed by means of latches or other suitable fastening devices indicated at 14.

5 Below the doors is a space or opening 15 in which is located a suction pipe 16, provided with a delivery chute 17, by means of which dust, etc., is removed.

In the construction shown in Figs. 1 and 10 2 it will be seen that the automatic control gearing for the base feed and product valves is secured to the top of the frame 10, whilst Figs. 3, 4 and 5 show the same control gearing arranged for suspension from girders or 15 the ceiling above the frame.

The machine may be driven directly by a motor, by belt connection or from a countershaft or line shaft.

Upon either side member, brackets 18, 20 18^a are provided. These brackets support three ball bearing pedestals or journals 19 one being provided on the bracket 18, and two on the bracket 18^a, these latter are spaced sufficiently far apart for a pulley to 25 revolve between them.

The bearings carry the beater shaft 21, which extends the whole width of the frame and through the bearings, and has mounted thereon a pulley 20, usually driven by a 30 belt from the counter shaft, or it may if found more convenient be driven directly from a motor. Secured on one of the side members is a sheet metal elbow 22, forming the lower portion of a duct for conveying 35 material to be treated to the machine. It is mounted over an opening 23 in the side member of the frame and allows the material to enter the machine freely for treatment. The upper portion 24 of the duct, 40 from the elbow upwards may be of wood or sheet metal.

Inside the frame or box, and supported by the side members is an elliptical chamber 25, in which the material is treated; but 45 when a series of beaters is employed the shape may be altered to suit requirements. The elliptical chamber when viewed in section, preferably has its major axis inclined at an angle of about 70 degrees to the horizontal (Figs. 1 and 8) and it is so mounted that one of the beaters lies in the lower, narrow end of the ellipse. The chamber itself is constructed in any approved manner one method shown in Figs. 8 and 9 being to 50 surround cast iron flanges 25^a on both side members with sheet metal 26, which extends from one side member to the other. The elliptical chamber 25 being smaller than the box, air spaces 27 and 27^a are left all 55 round on either flank of the ellipse and at top and bottom.

The lower portion of the elliptical casing, opposite the major axis, is perforated or provided with special removable grids 28 of varying mesh, correspondingly shaped.

These grids provide means whereby dirt and other waste material may be eliminated from the elliptical chamber during the operation of the machine while retaining the useful part of the material under treatment.

In the construction shown in Figs. 8 and 9, the dirt and other solid matter drops on to a wooden or other chute 29 and is thence conveyed by a spiral conveyor 30 or a series of conveyors, or a current of air or suction 75 may be employed for this purpose, as shown in Figs. 1 and 2. In another construction slides of box like form may be provided under the machine and emptied at intervals. Light dust and dust laden air is exhausted 80 by a fan and is either blown or sucked away and passed through a dust collector.

The air space between the elliptical chamber and the outer casing on the grid side, is closed at the top by a curved plate 31, Fig. 8, and at the bottom by the chute, so that there is no connection with the air space on the other side of the machine unless it is desired to make such connection.

A flap 32 is provided preferably hinged 90 below the beater extending the whole width of the machine below the elliptical chamber.

In the construction shown in Fig. 1, the flap or valve 32 is hinged on the side adjacent the grid, whereas in Fig. 8 the valve flap 32' is hinged on the side remote from the grid, in either construction a chute is provided into which the finished material is discharged when the flap 32 is opened, the chute being shown in Fig. 8 at 33. The flap is operated by any suitable means but preferably by automatic mechanism herein-after described.

The beater or rotor in the preferred form consists of a shaft 21, carrying a concentric tube or drum 34 on which are mounted beater arms or blades 35. The tube 34 is closed at each end by caps 36, each provided with a central boss to facilitate attachment thereof to the shaft 21 and with a flanged periphery extending into the counterbored open end of the drum 34, in which it is secured by bolts 37. The beater arms 35 project outwardly with spiral twist from a curved base portion 35^a (Figs. 11-14) and each arm is secured to the curved surface of the tube 34 by a pair of bolts 38 one on each side of the blade. The nuts on the bolts may be secured by lock nuts of suitable construction but I prefer to employ locking strips 39. These locking strips are of elongated U shape, the outer ends being bent outwardly and perforated to pass over the ends of the bolts of each beater arm. The limbs of the U in this manner closely embrace the flat outer faces of each nut 40 and secure the same against working loose. By this means there is no possibility of the loss of a bolt or of the nuts working loose. In an alternative construction I may employ two concentric 130

tubes, the beater arms being secured to the outer tube in which case the inner tube prevents the nuts being displaced from the holding down bolts of the beater arms.

5 As will be seen from Fig. 9, the arms or studs 35 are mounted spirally on the outer tube, the spirals commencing at the ends and extending around the tube 34 in opposite directions towards the centre. I prefer to provide several rows of blades arranged in this manner, and the spirals are so disposed that during rotation of the beaters the material is drawn towards the centre of the elliptical chamber, the forward edges of the spirals 10 during rotation being at the ends of the tube 34. By this means the material under treatment is carried round in a circular path by the blades co-operating with the curved inner surface of the elliptical chamber and 15 simultaneously moved or conveyed inwardly towards the centre this combined movement resulting in most satisfactory results.

The space between the periphery of the beater arms or studs and the inside of the 20 elliptical casing is determined at the narrowest point by consideration of the material to be treated, and the machine may be made with this dimension fixed or adjustable.

The machine just described is utilized in 25 the following manner:—

The untreated material or material that has already been treated once or twice, is dropped into a hopper 41 (Figs. 1 and 2) connected to or forming part of the feed 30 tube 24, in predetermined quantities.

The feed tube or duct is not necessarily at a point above the machine as the material may be conveyed mechanically or may be blown in.

35 The hopper of the feed tube is closed by a flap 42 operated by rods and levers from automatic gear hereinafter described, or it may be operated by hand, so that a more or less fixed quantity of material can be delivered, at regular intervals to the machine.

40 On entering the machine, the material is dropped upon the beater, which is revolving at a high speed and is carrying round with it a quantity of air. The surface presented by the beater is a serrated one, and upon falling upon it the material is struck or flicked by the rapidly revolving arms which also project it in a more or less disintegrated state at such an angle from the beater, that 45 it strikes the plain curved surface of the elliptical chamber, which it leaves at a tangent or is driven round following the curve of the ellipse. In doing so it passes across the grid 28, where solid matter, such as dirt, chiv, seeds, etc., liberated by the action of the beaters, drop out through the space in the grids, partly by the action of gravity and partly by the movement of the material across the grid.

55 Dust and dirt-laden air is driven out or

sucked out through the grid and dealt with by special methods.

Any loose fibres or small tufts that are practically of solid matter or dust tend to remain in a state of suspension owing to the 60 pneumatic effect of the rapidly revolving beaters but the unopened tufts and lumps are continually falling back into the paths of the beaters and are receiving a flicking from the tips of the said beaters or being picked up 65 and driven over the grid until such time as the heavy waste material and dust are practically eliminated.

At a given moment, the flap 32, for delivering the product is automatically opened 70 by the gear referred to later on, and the clean and expanded material is driven or sucked out in the direction required. The flap is then automatically closed, more fibre is admitted and the process is repeated.

75 It has been estimated from practical experience that every time the material comes under the influence of the beaters, it receives from 10,000 to 20,000 light taps or flicks which together with the pressure of 80 air carried round by the beater itself, produces a vibropneumatic action, which tends thoroughly to loosen individual fibres, whereby the minute dust adhering to them is extracted. The process moreover assists 85 very materially in straightening out the fibres in the subsequent machine processes.

I prefer to combine with the machine before described an automatic gear, the object of which is to vary the introduction of 90 the raw material known as "base" and also the exit or discharge from the machine of 95 the treated material or products. This mechanism is shown in Figs. 1 and 2 and more particularly in Figs. 3-7.

I provide a cast iron steel or other frame 100 43 which may be suspended from the ceiling over the machine as shown in Figs. 3 and 4, or placed on the top of the chamber 11 as shown in Figs. 1 and 2.

110 This steel frame carries, supported in bearings at either end, two superimposed cast iron speed cones, 44, 45 with their frusta opposed and their axes horizontal. The upper cone 44 receives motion by means 115 of fast and loose pulleys 46 (Fig. 2) attached to the spindle 47 at one end and driven by belt or other connections from a motor or countershaft. The upper cone drives the lower by means of a short leather 120 or other suitable belt 48 the position of which can be changed at will longitudinally by means of a hand chain 49 and pulley 50, which gives motion to a screwed shaft 51. This shaft causes a block 52 carrying a pair 125 of belt forks to traverse from end to end of the speed cones, in turn causing the belt 48 to move with it, and thereby as the belt at the larger or smaller end of the upper cone 44 causing the lower cone 45 to revolve at 130

the greatest or lowest speed, thus providing a large number of possible small variations of speed for the lower cone, between maximum and minimum.

5 The screwed shaft which actuates the belt fork is supported at either end in bracket bearings 53 bolted to the steel frame 43 and is extended at one end beyond the bearing, to a sufficient extent for the chain pulley 50 10 to be fitted. The chain 49 is of such length as to be within easy reach of the operator on the floor below the automatic gear. By pulling the chain in the required direction, the screwed shaft 51 is revolved and in doing so traverses the bolt fork, thereby securing the desired change of speed.

The spindle 54 of the lower speed cone 45 is extended through its bearing at one end and terminates in a worm 55 secured to the 20 shaft by any approved means. It is usually single threaded and "right hand." The threads of the worm are engaged with the teeth of a large horizontal worm wheel 56, which is consequently driven at a reduced speed.

The worm wheel is provided with a short hollow stub spindle 57 which fits in the socket 58 provided in the steel casting. Interposed between the underside of the worm 30 wheel and the steel casting and about its centre is a horizontal thrust bearing 59 which provided the main bearing for the worm wheel, but the latter is further supported by hardened steel rollers 60, located 35 at its periphery and interposed between the underside of the worm wheel and a horizontal extension of the steel casting.

On the upper side of the worm wheel, two 40 concentric grooves are cut to form seating for two horizontal, hardened steel ring cams 61, 62, secured from the underside of the wheel by a series of screws. A portion of the surface of each cam is cut away to form a depression of the required extent, flat at 45 the bottom and with inclined descent and ascent. The sharpness of the descent and ascent together with the extent or length of the depressed part of the cam, govern the speed of operation for any particular worm 50 wheel speed and the interval elapsing between the movements of the system of levers and the rods actuated by the cams.

55 Directly over the centre of the worm wheel and on either side over the outer and inner cams respectively, and formed in the steel casting are guides 63, 64 and 65 for the base and product poppets and the cross head 66 of the operating rod for the product flap on the fibre machine.

60 The outer ring cam 61, operates the product flap of the fibre machine, and the inner ring cam 62 the flap in the base feed flap by means of poppets and rods connected with them.

65 These poppets 67, 67^a are a sliding fit in

the guides 63 and 64 in the steel casting, and terminate at their lower ends in hardened steel rollers which bear in the face of the cams.

In action the worm wheel revolves under the poppets, until the depressed portion comes underneath them. They then descend the incline and remain at their lowest position for an interval depending upon the worm wheel speed after which they are 75 forced upwards to their highest position, that is to the upper surface of the cam, as the second incline comes underneath them.

The poppets are then given a reciprocating movement which is multiplied about to 80 twelve times in the case of the product poppet 67 by means of two levers and a link. The product poppet is attached by a pin 68 at its upper extremity to the short arm of a lever 69 hung on a pivot 70 secured in the steel casting. The long arm of the lever is attached at its extremity to a link 71, which in turn is attached to the short arm of another lever 72, also hung on a pivot 73. The long arm of the second lever terminates in a fork 74, with a parallel opening. The fork is engaged with a pin or trunnion carried by the cross head 66 attached to a rod 75, in such a manner that as the forked lever swings 90 upwards and downwards on its pivot the cross head is raised and lowered in a straight line.

The product rod cross head consists of a 95 square block usually of steel, and is a sliding fit in the guide 65 an extension of the steel casting. The latter consists of a square tube, machined to take the cross head and of sufficient length to accommodate its up and down movement. The tube is situated directly over the centre of the worm wheel and is slotted on one side to accommodate the forked lever, and allow of its movement.

The product rod 75 which passes through the centre of the worm wheel and is adjustably connected to the cross head is provided with a guide in the form of a cap 76 fitted to the bottom of the worm wheel spindle socket 58. The product rod forms a connecting link between the automatic gear and the product flap on the fibre machine, 115 which it operates by means of a lever, in its up and down movement.

The construction of the product flap is shown in Fig. 15. The flap 32 is mounted on a shaft 77 and extending parallel with this shaft is a second shaft 78 supported in suitable housings attached to the machine frame. The bearings are of the radial double row, self aligning type, mounted in dust 120 proof bearings, which are supported on cast iron brackets, secured to the side frames of the machine. Externally at one end of the machine is a lever 79 rigidly secured to the shaft by means of a key and being shrunk on, or it may be screwed on to the shaft 125 130

with a right or left hand screw depending upon the direction of the thrust. This lever is operated by the rod 75. The movement imparted by the automatic machine, turns 5 this lever through an angle of approximately 90 degrees.

Externally and at the opposite end of said shaft is a weight carrying lever 80 which is so set in relation to the first mentioned 10 lever that their centre lines make an angle of about 20 degrees with each other. The angular difference between the centre of levers, results in the weight carrying lever being very nearly perpendicular when the discharge flap 32 is open, and horizontal when 15 the discharge flap is closed. The weighted lever carries near its extremity a cheese weight 81, of the size required. The weight is slotted to receive the free end of the lever 20 and is rigidly secured thereto by means of a set-screw. The position of this weight is adjusted after the lever system has been erected, and the surplus material on the lever is cut away. When the discharge flap 32 is 25 open the centre of gravity of this weight is almost directly over the centre of the shaft 78, and consequently it exerts little or no influence on the lever system while in this position. When, however, the discharge flap 30 is closed, the lever and cheese weight are horizontal, and the pressure exerted by the weight is at a maximum.

Secured to the shaft between and close to the side frames of the machine, are cranked 35 levers 82, secured to the shaft by sunk keys. To the free ends of these levers, links 83 are attached by means of knuckle joints and pins. The crank levers are shaped at their free ends, so as to prevent having to use 40 an excessively long knuckle joint for the purpose of clearance and also to prevent locking of the lever and link when the discharge flap is open. The links are provided with knuckle joints, stems and the lock nuts. 45 Both ends of the stems and both knuckle joints in each case are threaded with a suitable right hand thread. The nuts are first run on the ends of the stem, following by the knuckle joints which after adjustment to 50 the length of the link required are locked in position by means of the nuts. By this means also adjustment is provided for wear taking place in the holes of the knuckle joints and levers and on the joint pins.

55 The other ends of the links are in each case attached by means of pins 84, to the lugs 85 rigidly secured to hinges of the curved discharge flap 32 by rivets or screws, and they are situated at the point where maximum thrust occurs on the surface of the discharge flap, due to the action taking place inside the machine.

60 The discharge flap which is of sheet metal, is curved to conform with the lower portion 65 of the treating chamber and is provided with

hinges, secured to the spindle or shaft 77 by any suitable means, such as a sunk key.

The external ends of the flap spindle 77 are carried by ball bearings of the radial double row, self aligning type, fitted in dust 70 proof housings. The housings are supported on cast iron brackets, secured to the side frames of the machine. The flap is thus capable of opening and closing radially the extent of movement being fixed by the movement of the operating lever. 75

The shaft is positioned on a line, making an angle of 60° with the vertical and passing through the centre of the lower portion of 80 the treating chamber.

In an extension of the valve shaft 77 a sector 86 is secured with a sunk key, or by being shrunk on or by any other suitable means. The sector has a groove 87 on its periphery for the reception of a stranded steel 85 flexible cable 88, the right or free end of which is secured to the sector in the following manner.

A small half round lug is cast with one of the arms of the sector, and it is drilled and tapped for a screw. Opposite this in the rim of the sector a hole 89 is drilled which communicates with the groove. The free end of the steel cable is laid in the groove and a sufficient quantity is threaded through the hole and bent round the surface of the lug 90. It is then secured from unwinding by a clip 91 of bridge pattern whose turned down 95 ends embrace the wire cable. The clip is secured in place on the lug by a screw. The height of the lug above the surface of the sector arm is such that when the screw is properly home, the steel cable is slightly pinched thus making a secure fastening. The other end of the cable terminates in a 100 thimble 92 over which the end of the cable is spliced.

The cable passes over the surface of a suitable grooved pulley 93, supported on a shaft carried in ball bearings of radial double row, 110 self aligning type which are supported by a bracket 94 bolted to the side frame of the machine. Hooked into the thimble is a spindle 95, which is screwed at its lower end and terminates in a circular plate 96, to which it 115 is secured by a nut, the whole forming a carrier for a balance weight 97, consisting of weights of cheese pattern. The weights have slots to enable them to be placed onto the carrier without having to be threaded on to 120 the spindle.

Sufficient weights are added to balance the valve or flap plus a small amount to ensure that when the flap is open and the weighted lever is in a vertical position, that there will 125 be sufficient weight to overcome the inertia of the lever system, and commence the movement of closing the valve flap.

In operation the automatic control mechanism will cause the rod 75 to move intermit- 130

tently upwards and downwards a distance of 12 inches, measured along the chord of the arc described by the end of the operating lever. By virtue of its length this lever thus 5 turns through 90°.

The up and down movement of the operating rod causes partial rotation either way of the shaft, and the oscillation of the lever connected to the discharge flap, which 10 through the medium of the links opens and closes the flap and also displaces the weighted lever.

In the upward stroke, power has to be expended in lifting the weighted lever, but the 15 effort required rapidly decreases from maximum, when it is horizontal, to minimum, when vertical. In the downward stroke, after the counterbalance weights have overcome the inertia of the lever system and flap, 20 the weighted lever is sufficiently to close the flaps and maintain it tightly closed against the maximum pressure exerted inside the operating chamber.

As the flap valve 32 turns about its axis 25 the sector 86 moves with it, winding or unwinding the steel cable and thus raising or lowering the counterbalance weight 97. As the flap opens, power is expended in raising the extra weight added over and above that 30 required to balance the flap, but is given out again as the flap closes and the weight falls.

The base poppet 67^a is attached directly by a pin 100 to a rod 101, having an adjustable screwed connection to a connecting 35 rod 102. The upper end of the rod 102 is connected to the shorter arm of a two armed lever 103, supported on a pivot 104, carried by bracket 105. The supporting bracket may be suspended from above the 40 machine as shown in Fig. 1, or it may be mounted on the floor above the machine as shown in Figs. 6 and 7. The longer arm of the lever 103 is connected in Fig. 1 to the short arm of a lever 106 carried by a shaft 107, said shaft being supported in bearing bracket 108. The shaft 107 has keyed thereto at one end a pulley 109, over or on which is wound a flexible band or cord 110 carrying counterbalance weights 111. 45 The other end of the shaft 107 carries an arm 112, the free end of which is connected by an adjustable link 113, to a lever 114, carried by the spindle on which the base flap 42 is mounted. The construction shown 50 in Figs. 6 and 7 is in all respects similar in operation, the longer arm of the lever 103, being connected by a pair of links 115 to a lever 116, supported by a bracket 117, the opposite end of the lever being connected to one arm of a bell crank lever fixed 55 to the spindle of the base feed flap.

The base feed flap 42 is designed to retain the charge of base in the feed hopper 41, for treatment in the fibre machine, until,

owing to the action of the base cam 62, the flap is opened and the charge dropped into the machine. 65

In operation the automatic gearing is set to the speed most suitable for the material under treatment the setting being obtained 70 by altering the position of the belt on the speed cones, 44, 45 by means of the hand chain 49 and screwed shaft 51. The range of speed permissible by this arrangement provides a most flexible control for the 75 base feed and discharge flaps and covers all classes of fibres.

What I claim and desire to secure by Letters Patent of the United States of America is:— 80

1. Apparatus for opening and cleaning fibrous material comprising a chamber into which the material is delivered, and a rotary beater in said chamber having blades arranged in rows and disposed in spiral formation, the spirals commencing at the 85 ends of the beater and meeting towards the centre.

2. Apparatus for opening and cleaning fibrous material as claimed in claim 1, wherein delivery and discharge of the material to and from the beater chamber is effected by flaps or valves, adapted to be automatically controlled through variable speed mechanism, said mechanism driving a worm wheel provided with cams adapted to operate tappets connected to each of said valves through links and levers, or their 90 equivalent. 95

3. Apparatus for opening and cleaning fibrous material as claimed in claim 2, wherein in the variable speed mechanism through which the worm wheel is driven comprises a pair of speed cones, around which passes a belt, said belt being adapted to be adjusted longitudinally of the cones, by a member carried by a rotatable screw threaded rod or spindle extending parallel to the axes of said cones substantially as described. 100

4. Apparatus for opening and cleaning fibrous material, as claimed in claim 2, wherein the worm wheel is arranged to rotate about a vertical axis, and is provided with a hollow stub axle through which passes a connecting rod forming part of the 105 lever mechanism, by means of which the product valve is operated. 110

5. Apparatus for opening and cleaning fibrous material as claimed in claim 2, wherein in the closing of the base and product valves 115 is assisted by counterbalance weights so arranged, as to become effective only when the valves or flaps commence their movement to the closed position, substantially as described. 120

In witness whereof I affix my signature. 125

WILLIAM YOULTEN.
